UNITED STATES PATENT OFFICE

WALTER TIERNEY, OF BUTTE, MONTANA, ASSIGNOR OF TEN PER CENT TO CLARENCE HANLEY, OF BUTTE, MONTANA

ARTICLE SUPPORT

Application filed March 31, 1928. Serial No. 266,238.

This invention relates to an improved article holder, which is especially, although not necessarily, adapted to support and position the staff of a flag.

5 What I aim to do, is to provide a simple and inexpensive device of this character which is capable of being temporarily fastened to automobile windshield glass, vehicle windows, house windows, doors, walls and 10 the like, whereby to permit small flags to be attached thereto for military and other display purposes.

Briefly described, the invention comprises suction cups provided with an outstanding 15 projection having a socket for reception of the flag staff.

In the drawings:—

Figure 1 is a view in section and elevation showing a flag holder constructed in accordance with the invention, and representing the approximate manner of use.

Fig. 2 is an enlarged front elevation of the holder, shown in Fig. 1.

Fig. 3 is a top plan view of the same.

25 Fig. 4 is a perspective view of a removable bushing.

Referring now to the drawings by reference numerals, it will be observed that the numeral 5 designates a concavo-convex suction cup, which is adapted to be stuck to the supporting surface 6.

The supporting surface may be of glass, wood, metal, or other plain smooth surface. Formed integral with and located centrally 35 upon the cap is an outstanding sturdy projection 7, having a vertical opening formed therein, which constitutes a pocket for removable reception of the lower end of the flag staff 8.

40 A reducing bushing 9 of tapered design may be fitted into said pocket if desired. In fact, it is thought advisable to supply several sizes of bushings with the device, whereby to accommodate flag staffs of different diameters, and in addition, it is to be observed that the bushings are removable.

The simplicity of construction is such as to permit a clear understanding of the invention to be had, after considering the description in connection with the drawings.

Consequently, a more lengthy description is regarded unnecessary.

Having thus described my invention, what I claim as new is:—

As a new product of manufacture, an article holder comprising a concavo-convex rubber suction cup adapted to adhere to a relatively stationary support, said cup being provided with a centrally located integral outstanding sturdy projection having a vertical tapered hole formed therethrough, and a removable tapered reinforcing bushing fitted into said hole and adapted for reception of a flagstaff.

In testimony whereof I affix my signature.

WALTER TIERNEY.
